MACHINE FOR SHAPING UPPERS OVER
LASTS

Jacob C. Jorgensen, Beverly, Mass., assignor to
United Shoe Machinery Corporation, Paterson,
N. J., a corporation of New Jersey

Application March 21, 1933, Serial No. 661,897

18 Claims. (Cl. 12—4)

This invention relates to machines for use in the manufacture of shoes for shaping uppers over lasts, and is herein illustrated in its application to a pulling-over machine constructed especially for use in pulling over the uppers of stitchdown shoes. It is to be understood, however, that in some of its novel aspects the invention is not limited to pulling-over machines nor to machines for operating on shoes of that particular kind.

5 Pulling-over machines of the well-known type exemplified by the disclosure of United States Letters Patent No. 1,029,387, granted on June 11, 1912, upon an application of R. F. McFeely have been modified heretofore with the object 10 of adapting them better for use to pull over the uppers of stitchdown shoes, as illustrated in Letters Patent No. 1,916,275, granted on July 4, 1933 upon an application of James M. Matheu. As disclosed in the last-mentioned Letters Patent, 15 after the pulling-over grippers have been operated to pull the upper heightwise of the last, the upper is fastened by tacks driven in directions inclined relatively to the bottom face of the last in locations substantially at the junction of the 20 bottom face and the upper-shaping surface of the last, so that the marginal portion of the upper may be readily turned outward and a sole or insole applied over the outturned margin while some or all of the tacks are still in the last. The 25 upper-fastening devices are movable inwardly toward the shoe into upper-fastening positions and carry means for clamping the upper before the fastenings are driven, such devices also acting in their inward movements to release the grippers 30 from the upper through contact with releasing members on the grippers.

One object of the present invention is to afford increased insurance that in a machine operating as above described the upper will be 35 clamped and held securely in the proper relation to the last in the interval between its release by the grippers and the driving of the fastenings. For purposes of the invention the construction herein shown is accordingly such that the grippers 40 in their upper-pulling movements heightwise of the last receive also movements in directions to draw the upper inwardly over the edge of the last bottom. This serves not only to position the 45 marginal portion of the upper close to that portion of the last against which it is to be clamped by the clamping means, but also to carry the gripper-releasing members farther away from the upper-fastening devices, so that better insurance is afforded against release of the grippers from 50 the upper by the inward movements of these to each other. In the construction of the work 55

devices before the clamping members arrive in clamping positions. The above described inward movements of the grippers are effected by overdraw springs with which machines of the illustrated type are customarily provided, and to render these springs effective to impart such movements to the grippers in the course of the upper-pulling operation, there are provided on the gripper bars inclined faces cooperating with members at the inner sides of the grippers to control the 10 latter in opposition to the overdraw springs, these faces extending in such inclined relation to the directions of the upper-pulling movements of the grippers heightwise of the last as to permit the grippers to be moved inwardly by the springs, 15 as they receive their upper-pulling movements, through distances that are proportional to the extent of such pulling movements.

The driving of the tacks precisely in the desired locations at the junction of the bottom face 20 and the upper-shaping surface of the last requires that the last be accurately positioned heightwise relatively to the upper-fastening devices. In machines of the illustrated type the heightwise position of the last is determined by 25 a work rest positioned opposite the bottom face of the last and comprising members arranged respectively at the end and the sides of the forepart of the last bottom. Since the bottoms of the foreparts of lasts are frequently curved more 30 or less laterally as well as lengthwise, the construction herein shown is such that the members of the work rest are arranged to engage the bottom face of the last in locations as close as is practicable to the points where fastenings are 35 driven. As illustrated, the side members of the work rest are thus arranged to engage the last in locations opposite the points where the rear-most side tacks are driven and at less distances 40 from the edge of the last bottom than the width of the marginal portion of the upper extending beyond said edge, and the end member is arranged to engage the last in a location directly opposite the point where the end tack is driven 45 and in similarly close relation to the edge of the last bottom. For greater accuracy with respect to the locations of the tacks in operating on lasts of different styles and of different sizes, provision is also afforded by this invention for various adjustments of the work rest members, especially of the side members, the latter in the construction shown being adjustable heightwise 50 of the last relatively to the end member and also adjustable widthwise of the last relatively 55

rest, and especially in the provision for different adjustments of its side members, novel features are to be recognized which are not limited to use on stitchdown shoes where the work rest engages the bottom face of the last, but are applicable also to work rests engaging a sole or insole on the last.

The above and other novel features of the invention, including various novel details of construction and combinations of parts, will now be more particularly described by reference to the accompanying drawings and pointed out in the claims.

In the drawings,

15 Fig. 1 is a view from the front, partly in section, of a portion of a machine in which the invention is embodied, comprising means for pulling and fastening the upper at the opposite sides of the forepart, the parts being shown in the positions that they occupy at the time of the upper-fastening operation;

20 Fig. 2 is a view in side elevation of the upper-pulling and fastening means at the end of the toe, together with portions of the work-positioning means;

25 Fig. 3 is a section on the line III—III of Fig. 2;

30 Fig. 4 is a view similar to Fig. 1 of portions of the structure there shown, but with the parts in the positions that they occupy at the beginning of the upper-pulling operation;

35 Fig. 5 is a view similar to Fig. 4 with the parts in the positions that they occupy after the upper-pulling operation and prior to the movement of the upper-fastening means into position for the driving of the fastenings; and

40 Fig. 6 is a view in the direction of the arrow A in Fig. 2, illustrating more clearly the relation between the last and shoe and certain portions 45 of the structure at the time when the fastenings are driven.

45 As is well known, a machine of the type in which the invention is herein shown as embodied includes in its organization a gripper 10 (Fig. 2) for pulling the upper at the end of the toe and grippers 12 for pulling it at the opposite sides of the forepart. The grippers are operated by updraw levers, one of which is shown in section at 14, whereby they are moved automatically 50 heightwise of the last to pull the upper yieldingly upon the starting of the power operation of the machine. The machine comes automatically to a stop with the upper held under tension by the grippers to afford opportunity for inspection 55 of the work and for any manual movements of the grippers that may be necessary to adjust the upper properly on the last. When the machine is again started, side clamp arms 16 are swung inwardly toward the sides of the shoe to clamp 60 the forepart of the upper against the last and support the last for the upper-fastening operation. In the continued operation of the machine upper-fastening devices are moved inwardly into 65 positions to drive upper-holding fastenings, these devices carrying additional means for clamping the upper to assist in holding it until the fastenings are driven. Release of the grippers from the upper is effected by engagement of the inwardly moving upper-fastening devices with 70 members 18 at the outer sides of the grippers, whereupon the grippers are moved farther upwardly and are also swung inwardly to make way for the upper-fastening devices. After the 75 fastenings have been driven the parts of the

machine are returned to their starting positions and the shoe is released.

5 In general similarity to the construction shown in the above-mentioned Letters Patent No. 1,916-275, the upper-fastening devices in the machine 10 herein shown are so constructed and arranged as to drive a single tack at the end of the toe and two tacks at each side of the forepart, the tacks being driven in locations substantially at the junction of the bottom face and the upper-shaping 15 surface of the last, i. e., the surface that gives shape to portions of the upper that are visible in the finished shoe above the shoe bottom. Lasts which are used in the manufacture of stitchdown 20 shoes usually have a somewhat rounded or beveled contour at the junction of the bottom face and the upper-shaping surface, and as disclosed in the above-mentioned Letters Patent the tacks are driven in this portion of the last at such inclinations to the bottom face of the last that the 25 margin of the upper may be readily turned outward and a sole or insole placed on the bottom of the last in engagement with the outturned margin while some, at least, of the tacks are still in the last. The upper-fastening devices at the sides 25 of the forepart are supported on arms 20 (Fig. 1) which are swung inwardly toward each other to carry the devices into upper-fastening positions and which carry spring-operated driver 30 bars 22 connected by means of substantially the same character as disclosed in the above-mentioned Letters Patent with tack drivers 24 inclined in the desired angular relation to the bottom face of the last for the purposes in view. The upper-fastening device at the end of the toe 35 is supported on an arm 26 (Fig. 2) mounted to swing lengthwise of the shoe, this arm carrying a driver bar 28 connected to a tack driver 30 inclined relatively to the bottom face of the last at substantially the same angle as the side tack 40 drivers 24. Each of the several upper-fastening 45 devices includes a pair of tack fingers 32 that provide a tack pocket from which the tack is driven by the driver.

50 In order that the tacks may be driven in proper relation to the bottom face and the upper-shaping surface of the last the inward movements of the upper-fastening devices must be stopped with these devices in proper relation to the last. Accordingly the front arm 26 carries a stop 34 arranged to engage the end of the shoe and thus limit the rearward swinging movement of the arm while also clamping the upper against the end face of the last to assist in holding the upper until the tack is driven. This stop is adjustable lengthwise of the shoe relatively to the arm 26 and is held in adjusted position by a clamping screw 36. While differing in construction somewhat from the corresponding stop shown in the previously mentioned Letters Patent No. 1,916,275, it 55 performs the same function as the stop therein shown. The means for limiting the inward movements of the upper-fastening devices that operate at the sides of the shoe is somewhat different from the disclosure of the above-mentioned Letters Patent. As herein illustrated, each side clamp arm 16 carries a pair of clamp members 38 and 40 connected together by equalizing mechanism not shown in detail, but of substantially the same 60 construction as used frequently heretofore in machines of the illustrated type and similar to the disclosure of Letters Patent No. 1,135,954, granted on April 13, 1915 upon an application of R. F. McFeely. Each clamp member 40 clamps the upper 65

against the side of the last below the locations where the side tacks are driven and is mounted on a block 42 swiveled for movement about an axis extending heightwise of the last for automatic adjustment to the lengthwise contour of the side of the last as determined by engagement of the clamp member 40 with the shoe, as common heretofore in some machines of the illustrated type. The upper-fastening devices at each side of the last include two plates 44 and 46 each of which serves as a guide for one of the tack drivers 24 and as a support for the corresponding pair of tack fingers 32. In the construction herein shown the plates 44, which are included in the rearmost upper-fastening devices (i. e., the devices located farthest from the end of the toe), are fast on the arms 20, while the plates 46 included in the upper-fastening devices that are nearer the end of the toe are pivoted at 48 on the arms 20 for swinging movements widthwise of the shoe and are urged inwardly by springs 50. Each of the plates 44 and 46 carries at its lower end a stop 52 arranged to engage a shoulder on the previously mentioned side clamp block 42. It will thus be seen that the stops 52 carried by the plates 44 that are fast on the side arms 20 limit the inward swinging movements of these arms and determine the positions laterally of the shoe of the rearmost upper-fastening devices. The stops 52 on the plates 46, on the other hand, by their engagement with the blocks 42, determine the positions of the foremost side upper-fastening devices, permitting these devices to adjust themselves relatively to the shoe in accordance with the positions of the swiveled blocks 42 determined by the contour of the shoe. In the construction shown the clamp members 40 are made of metal for positive engagement with the shoe, so as to afford better insurance of accuracy in the positioning of the upper-fastening devices relatively to the shoe. Each stop 52 is threaded in the plate 44 or 46 which supports it to permit its adjustment laterally of the shoe by means of a screw driver and is clamped in adjusted position by a clamping screw 54 engaging two parts of a split bearing in which the threaded portion of the stop is mounted.

To assist in holding the upper until the tacks are driven, each of the side upper-fastening devices in the construction herein shown carries a clamp member 56 which clamps the marginal portion of the upper against the last above the clamp member 40 at the junction of the bottom face and the upper-shaping surface of the last and acts to some extent as a wiper upon the upper as it is moved inwardly. By reference to Fig. 4, which shows the two members 56 that are carried by the foremost side upper-fastening devices, it will be noted that each member 56 is supported on the plate 46 below the tack fingers 32. Each member 56 is provided with two arms 58 that extend along opposite sides of the plate 46, a portion of one of the arms of the left-hand member being broken away in Fig. 4. The two arms 58 carry a pin 60 on which there is mounted a roll 62 located in a slot 64 in the plate 46. The member 56 has an upwardly curved end portion for engaging the upper and has in this portion a slot through which the tack is driven, as shown in Fig. 6. A spring 66 connected to the plate 46 and to a pin 68 that extends between the two arms 58 urges the member 56 inwardly and positions it normally with the roll 62 at the inner end of the slot 64. Another spring 70 connected to the plate 46 and the pin 68 tends to swing the member 56 about the axis of the pin 60 in the direction to depress the upper-engaging end portion of the member. Such swinging movement of the member 56 is limited by engagement of portions of the arms 58 with the plate 46 in slots 72 in the sides of the plate. It will thus be seen that when the plate 46 is carried inwardly toward the shoe by the swinging of the arm 20 the inner end of the member 56 engages the upper held in tensioned condition by the gripper before the arm 20 completes its inward swinging movement and that as the arm continues its movement the springs 66 and 70 yield and thereafter by their tension serve to urge the upper-engaging portion of the member both inwardly and downwardly to press it firmly against the upper. A similar member 56 controlled by means substantially as described with reference to each of the foremost side upper-fastening devices is associated also with each of the rearmost side upper-fastening devices and with the upper-fastening device at the end of the toe.

As in prior machines of the illustrated type, each of the side grippers comprises a pair of upper-gripping jaws 74 and a gripper bar 76 to which movement heightwise of the last is imparted by the corresponding updraw lever 14 to close the jaws 74 on the upper and then to impart to them their upper-pulling movement. Similarly the toe gripper comprises jaws 78 which are closed and operated by a gripper bar 80 connected to the corresponding updraw lever. Located between the side gripper bars 76 and at the rear of the toe gripper bar 80 is gripper-spreading mechanism of substantially the same character as disclosed in the previously mentioned Letters Patent No. 1,029,387, whereby the side grippers are positioned initially at the proper distance apart to receive the margin of the upper at the sides of the last and the toe gripper also is presented in the proper initial position lengthwise of the last to receive the upper. This mechanism is not herein shown in detail, but includes members 82 which engage the inner faces of the side gripper bars 76 and a roll 84 which engages the rear or inner face of the toe gripper bar 80. Associated with each of the side grippers are two overdraw springs 86, only one of which is shown in the drawings, these springs bearing against a plate 88 engaging the gripper on its outer side and thus tending to swing the gripper inwardly and holding the bar 76 against the member 82. Similar overdraw springs 90 (Fig. 2) associated with the toe gripper tend to swing it rearwardly and hold the bar 80 against the roll 84. In the operation of a machine of the illustrated type the gripper-spreading mechanism is so controlled that at the time in the cycle of the machine when the upper-fastening devices are moved inwardly toward the shoe it permits the grippers to be swung inwardly by the overdraw springs to make way for the upper-fastening devices.

For the accomplishment of one of the objects of the present invention the construction herein shown is such as to cause the grippers to be swung somewhat inwardly by the overdraw springs in the course of the upper-pulling movements of the grippers heightwise of the last, prior to the inward movements of the upper-fastening devices. To this end, each of the side gripper bars 76 has at its inner side a face 92 in engagement with the member 82 and arranged in such inclined relation to the direction of the upper-pulling movement of the gripper heightwise of the last as to permit an inward swinging movement of the

gripper by the springs 86 proportional to the extent of the upper-pulling movement as the latter movement takes place. A similarly inclined face 94 on the toe gripper bar 80 engages the roll 84 and performs the same function with respect to the toe gripper. By reference to Fig. 4 it will be seen that by the cooperative action of the inclined faces 92 and the members 82 the side gripper jaws are positioned initially at such a distance apart that the jaws are located opposite the side faces of the last when in upper-receiving positions. As the upper-pulling movement of the grippers is effected they are swung inwardly by the overdraw springs as soon as the jaws rise above the plane of the bottom face of the last, so that they draw the marginal portion of the upper inwardly over the edge of the last bottom before the upper-pulling operation is completed, as illustrated in Fig. 5. A similar action occurs at the toe end of the last. The portions of the upper that are to be engaged by the clamping members 56 are accordingly drawn inward over that portion of the surface of the last against which they are to be clamped by these members before the latter receive their operative movements. The inward swinging movements of the grippers also carry the gripper-releasing members 18 farther from the upper-fastening devices. Better insurance than heretofore is thereby afforded that the marginal portion of the upper will be clamped and held in proper relation to the last before the members 18 are operated by the incoming upper-fastening devices to release the grippers from the upper, so as to avoid any loss of tension in the upper before the fastenings are driven. It will be understood that after such inward movements of the grippers as occur during the upper-pulling operation by reason of the inclined faces 92 and 94 on the gripper bars, still further inward movements thereof result from the retraction of the gripper-spreading mechanism to position them well out of the way of the upper-fastening devices after they are released from the upper, as illustrated in Fig. 1.

It will be evident that the driving of the tacks precisely in the desired locations at the junction of the bottom face and the upper-shaping surface of the last requires that the last be accurately positioned heightwise relatively to the upper-fastening devices. For this purpose the machine is provided with a work rest comprising a member 96 arranged to engage the bottom face of the last near the end of the toe and members 98 arranged to engage the bottom face of the last farther rearwardly at the sides of the forepart. The end member 96, as in prior machines of the illustrated type, is mounted on a bar 100 which is adjustable lengthwise of the last in a holder 102, the bar as herein shown being held in adjusted position by a screw 104 threaded in a plate 106 on the holder 102 and having a pointed end 108 cooperating with rack teeth 110 on the bar. The member 96 is pivoted at 112 on the bar 100 for swinging movements heightwise of the last. A spring 114 tends to swing the member in one direction, and a screw 116 carried by the member and bearing on the bar 100 cooperates with the spring to determine adjustably the position of the member. The side members 98, in the construction herein shown, are adjustable relatively to the end member 96 in directions heightwise of the last, and for this purpose they are mounted on a support 118 which is itself mounted on screws 120 on the sides of the holder 102 for swinging movement about an axis extending widthwise of

the last. A spring 122 tends to swing the support 118 in one direction, and cooperating with the spring to determine adjustably the position of the support there is a stop screw 124 which is threaded in the support and abuts against the bar 100. By means of the screw 124 the last-engaging portions of the members 98 may accordingly be adjusted heightwise of the last. 5

In view of the fact that the bottoms of lasts at the forepart are frequently curved more or less laterally as well as lengthwise, the construction herein shown is further such that the members 98 engage the bottom face of the last in locations as close as is practicable to the side edges of the last bottom, as herein illustrated at less distances from the edge of the last bottom than the width of the marginal portion of the upper that extends beyond said edge. As illustrated, moreover, these members engage the last in locations opposite the points where the rearmost side tacks are driven, i. e., in locations directly inward over the last bottom from these points, so as to provide for particular accuracy in the driving of the rearmost tacks which in practice are sometimes permitted to remain in the shoe and last until a later stage in the manufacturing operations than the foremost side tacks and the end tack. In order that the members 98 may be accurately positioned in operating on lasts of different sizes, the construction shown is such that they are pivoted on screws 126 on the support 118 for swinging movements widthwise of the last. A spring 128 located between the members 98 forwardly of the points where they are pivoted tends to swing their last-engaging ends apart. To cooperate with the spring 128 in adjusting the members 98 widthwise of the last there is provided a screw 130 which is threaded in the support 118 rearwardly of the pivot points of the members and has a conical end portion that engages inclined faces on the members, the screw thus acting as a wedge member in opposition to the spring 128. By adjustment of the screw 130 the last-engaging ends of the members 98 may accordingly be positioned at the desired distances apart for operating on lasts of different sizes. It will be understood that the member 96 is also adjusted to engage the last as near as is practicable to the point where the end tack is driven, and that by adjustment of this member heightwise of the last as hereinbefore described the desired accuracy with respect to the location of the end tack is obtained. It will be evident that when the members 96 and 98 are adjusted to determine accurately the position of the last relatively to the devices that drive the end tack and the rearmost side tacks, the last is positioned also with sufficient accuracy relatively to the devices that drive the foremost side tacks. 35

Having described the invention, what I claim as new and desire to secure by Letters Patent of the United States is:

1. In a machine for shaping uppers over lasts, grippers for pulling an upper simultaneously at the opposite sides of a last, means for effecting an initial relative movement of said grippers and the last heightwise of the last to pull the upper, and additional means automatically operative in predetermined time relation to said relative movement to move said grippers widthwise of the last to draw the upper inwardly over the edge of the last bottom in the course of said relative movement. 65

2. In a machine for shaping uppers over lasts, grippers for pulling an upper at the opposite sides of a last, means for effecting an initial relative movement of said grippers and the last heightwise of the last to pull the upper, spring means tending to move said grippers toward each other widthwise of the last, and means for controlling such movements of the grippers toward each other, said controlling means being so constructed as to position the grippers in predetermined spaced relation at the beginning of the upper-pulling operation and to permit them to be moved toward each other by said spring means to draw the upper inwardly over the edge of the last bottom prior to the completion of said relative movement.
3. In a machine for shaping uppers over lasts, grippers for pulling an upper at the opposite sides of a last, means for moving said grippers initially heightwise of the last to pull the upper, spring means tending to swing said grippers toward each other widthwise of the last, and means at the inner sides of the grippers for controlling their swinging movements, said controlling means being so constructed as to position the grippers initially at a predetermined distance from each other and to permit them to be swung inwardly toward each other by said spring means to draw the upper inwardly over the edge of the last bottom prior to the completion of their initial upper-pulling movements heightwise of the last.
4. In a machine for shaping uppers over lasts, grippers for pulling an upper at the opposite sides of a last, each of said grippers comprising a pair of jaws for gripping the upper and a bar movable heightwise of the last for operating the jaws to pull the upper, spring means tending to move said grippers toward each other widthwise of the last, and gripper-spreading mechanism arranged to engage said gripper bars at their inner sides to position the grippers initially at a predetermined distance from each other, said gripper bars having faces thereon arranged to engage said spreading mechanism and extending in such inclined relation to the directions of the upper-pulling movements of the bars heightwise of the last as to permit the grippers to be moved toward each other by said spring means to draw the upper inwardly over the edge of the last bottom in the course of their upper-pulling movements heightwise of the last.
5. In a machine for shaping uppers over lasts, a gripper for pulling an upper over a last, means for imparting to said gripper upper-pulling movement heightwise of the last, and additional means for imparting to said gripper automatically prior to the completion of its upper-pulling movement heightwise of the last a movement the extent of which is proportional to the extent of said upper-pulling movement to draw the upper inwardly over the edge of the last bottom.
6. In a machine for shaping uppers over lasts, a gripper for pulling an upper over a last, means for imparting to said gripper an initial upper-pulling movement heightwise of the last, spring means tending to swing said gripper inwardly in a direction transverse to the edge of the last bottom, and means at the inner side of the gripper for controlling its swinging movement, said controlling means being so constructed as to permit the gripper to be swung inwardly by said spring means to draw the upper over the edge of the last bottom in the course of said movement of the gripper heightwise of the last.
7. In a machine for shaping uppers over lasts,
- a gripper for pulling an upper over a last, said gripper comprising a pair of jaws for gripping the upper and a bar movable heightwise of the last for operating said jaws to pull the upper, spring means tending to swing the gripper inwardly in a direction transverse to the edge of the last bottom, and mechanism arranged to engage the gripper bar at its inner side to control the gripper in opposition to said spring means, said bar having thereon a face engaging said mechanism and arranged in such inclined relation to the direction of the upper-pulling movement of the gripper heightwise of the last as to permit the gripper to be swung inwardly by the action of said spring means in the course of its upper-pulling movement.
8. In a machine for shaping uppers over lasts, grippers for pulling an upper at the opposite sides of a last, means for effecting relative movement of said grippers and the last heightwise of the last to pull the upper, upper-clamping and fastening devices movable inwardly into positions to clamp the tensioned upper against the last in locations substantially at the junction of the bottom face and the side faces of the last and having means for driving fastenings also into that portion of the last to hold the upper, said devices being automatically operative in their inward movements to release the grippers from the upper by contact therewith, and means constructed and arranged to impart to said grippers prior to the inward movements of said upper-clamping and fastening devices movements widthwise of the last away from said devices to draw the upper inwardly over the edge of the last bottom.
9. In a machine for shaping uppers over lasts, grippers for pulling an upper at the opposite sides of a last, said grippers comprising upper-gripping jaws and gripper bars for operating said jaws to pull the upper, means for moving said bars heightwise of the last to impart to the jaws their upper-pulling movements, upper-clamping and fastening devices movable inwardly into positions to clamp the tensioned upper against the last in locations substantially at the junction of the bottom face and the side faces of the last and provided with means for driving fastenings also into that portion of the last to hold the upper, said devices being automatically operative in their inward movements to release the grippers from the upper by contact therewith, spring means tending to swing the grippers toward each other widthwise of the last, and mechanism arranged to engage the gripper bars at their inner sides to position the grippers initially at a predetermined distance from each other in opposition to said spring means, said gripper bars having faces thereon arranged to engage said mechanism and inclined in such relation to the directions of the upper-pulling movements of the grippers heightwise of the last as to permit the grippers to be swung toward each other by said spring means to draw the upper inwardly over the edge of the last bottom in the course of their upper-pulling movements.
10. In a machine for shaping uppers over lasts, a gripper for pulling an upper over a last, said gripper comprising a pair of jaws for gripping the upper and a bar movable heightwise of the last for operating said jaws to pull the upper, upper-clamping and fastening mechanism movable inwardly into position to clamp the tensioned upper against the last in a location substantially at the junction of the bottom face and the upper-shaping surface of the last and provided with

means for driving a fastening also into that portion of the last to hold the upper, said mechanism being automatically operative in its inward movement to release the gripper from the upper by contact therewith, spring means tending to swing the gripper inwardly in a direction transverse to the edge of the last bottom, and a member arranged to engage the gripper bar at its inner side to control the gripper in opposition to said spring means, said bar having thereon a face engaging said member and arranged in such inclined relation to the direction of movement of the bar heightwise of the last as to permit the gripper to be moved inwardly by the action of said spring means in the course of its upper-pulling movement heightwise of the last.

11. In a machine for shaping uppers over lasts, the combination with means for pulling an upper over a last, and upper-fastening devices movable widthwise of the last into upper-fastening positions at the opposite sides of the forepart and provided with means for driving fastenings in locations substantially at the junction of the bottom face and the side faces of the last and in directions inclined to the last bottom, of a work rest comprising members arranged to position the last relatively to said upper-fastening devices by engagement with the bottom face of the last at the sides of the forepart in locations opposite the points where fastenings are driven and at less distances from the edge of the last bottom than the width of the marginal portion of the upper extending beyond said edge.

12. In a machine for shaping uppers over lasts, the combination with means for pulling an upper over a last, and upper-fastening devices movable widthwise of the last into upper-fastening positions at the opposite sides of the forepart and provided with means for driving at each side, at different distances from the toe end face of the last, a plurality of fastenings in directions inclined to the last bottom and in locations substantially at the junction of the bottom face and the side face of the last, of a work rest comprising members arranged to position the last relatively to said upper-fastening devices by engagement with the bottom face of the last at the end and the sides of the forepart respectively, the members at the sides of the forepart being arranged to engage the last in locations opposite the points where the rearmost fastenings are driven and at less distances from the edge of the last bottom than the width of the marginal portion of the upper extending beyond said edge.

13. In a machine for shaping uppers over lasts, the combination with means for pulling an upper over a last, and upper-fastening devices provided with means for driving fastenings in locations substantially at the junction of the bottom face and the side faces of the last and in directions inclined to the last bottom to fasten the upper at the sides of the forepart, of a work rest comprising members arranged to position the last relatively to said upper-fastening devices by engagement with the bottom face of the last at the end and the sides of the forepart respectively, the side members being adjustable heightwise of the last relatively to the end member and also ad-

justable widthwise of the last relatively to each other.

14. In a machine for shaping uppers over lasts, the combination with means for pulling an upper over a last, and upper-fastening devices provided with means for driving fastenings in locations substantially at the junction of the bottom face and the upper-shaping surface of the last and in directions inclined to the last bottom to fasten the upper at the end and the opposite sides of the forepart of the last, of a work rest comprising members arranged to position the last relatively to said upper-fastening devices by engagement with the bottom face of the last at the end and the sides of the forepart respectively, the end member being adjustable both lengthwise and heightwise of the last relatively to the side members, and the side members being adjustable heightwise of the last relatively to the end member and also adjustable widthwise of the last relatively to each other.

15. In a machine for shaping uppers over lasts, the combination with means for shaping an upper over a last, of a work rest comprising members arranged to occupy different locations opposite the bottom face of the last at the end and the sides of the forepart respectively, the side members being adjustable as a unit heightwise of the last relatively to the end member and being adjustable widthwise of the last relatively to each other.

16. In a machine for shaping uppers over lasts, the combination with means for shaping an upper over a last, of a work rest comprising members arranged to occupy different locations opposite the bottom face of the last at the end and the sides of the forepart respectively, and a support for the side members movable to adjust them in unison heightwise of the last relatively to the end member and on which they are mounted for adjustment relatively to each other widthwise of the last.

17. In a machine for shaping uppers over lasts, the combination with means for shaping an upper over a last, of a work rest comprising members arranged to occupy different locations opposite the bottom face of the last at the end and the sides of the forepart respectively, a support for the side members movable to adjust them heightwise of the last relatively to the end member, the side members being mounted on said support for swinging movements relatively to each other widthwise of the last, and means for adjusting them about the axes of their swinging movements.

18. In a machine for shaping uppers over lasts, the combination with means for shaping an upper over a last, of a work rest comprising members arranged to occupy different locations opposite the bottom face of the last at the end and the sides of the forepart respectively, the side members being mounted for swinging movements relatively to each other widthwise of the last, spring means tending to swing them each in one direction relatively to the other, and a wedge member movable to adjust the side members widthwise of the last against the resistance of said spring means.

JACOB C. JORGENSEN.
